SWAN ANDERSON, OF DENVER, COLORADO, ASSIGNOR OF ONE-HALF TO CHARLES H. TOMLINSON, OF MANSFIELD, OHIO, AND ONE-EIGHTH TO JOHN TOMLINSON, OF DENVER, COLORADO.

LOCKING MECHANISM.

1,163,612.

Specification of Letters Patent.

Patented Dec. 7, 1915.

Application filed September 14, 1914. Serial No. 861,503.

To all whom it may concern:

Be it known that I, SWAN ANDERSON, a citizen of the United States of America, residing at Denver, in the county of Denver and State of Colorado, have invented certain new and useful Improvements in Locking Mechanism, of which the following is a specification.

The present invention relates to a locking mechanism for oscillating or swinging levers, and more particularly to a locking mechanism for switch-tongues of street railway switches.

It is well known by those skilled in the art, to which this invention appertains, that the ordinary street railway switch-tongue is very frequently moved from its position by vibration of the rails caused by a passing car or train, and consequently a portion of the train is guided from the main track onto a side track with disastrous result.

The principal object of the present invention is to provide a simple and effective mechanism by means of which the switch-tongue is effectively locked in either position after it has been moved over the dead center by the trainman or switchman.

Another object is to provide a locking mechanism for switch-tongues which can be applied to any ordinary switch-tongue without disturbing the paving or road-bed along side the rails, and which is readily accessible for inspection or renewal.

These and other objects are accomplished by the construction and arrangement of parts hereinafter fully described and shown in the accompanying drawing, in which—

Figure 1 shows a plan view of a section of railway track including the switch-tongue. Fig. 2 is an elevation of the same, shown partly in section. Fig. 3 is a top plan view of the spiral spring and Fig. 4 is an elevation of the same.

Referring more particularly to the drawing, reference numeral (1) represents a portion of the main track rail, (2) indicates the side track rail and (3) represents the oscillating switch-tongue which co-operates between the rails (1) and (2) to guide the car wheel from one rail to the other. The switch-tongue (3) is pivoted to the base plate (4) by the pivot pin (5), and operates in a manner which is well understood. All of these parts, so far described, may be of any ordinary and well known construc-

tion, and one of the essential features of my invention lies in the fact that it may very readily be applied to any switch already in use without the addition of any complicated working parts, or without disturbing the paving or road-bed along side the rails.

As will be seen in Fig. 2, I provide a recess (6) in the under side of the switch-tongue (3) which is adapted to receive the spiral spring (7). In the bottom of the recess (6) I also provide an aperture (8) which is suitably positioned to receive the end (9) of the spring. Also in the top of the base plate (4) and substantially on the horizontal center line between the rail (1) and the guard rail (10) I provide an aperture (11) which is adapted to receive the outer end (12) of the spring (7). In the preferred form the spring (7) is made in the form of an ordinary spiral spring as shown in Fig. 3, this spring being made from either round, square or flat wire as desired. The spring is of course designed so as to provide sufficient tension to lock the switch-tongue in either position as described later.

It will be noticed in Fig. 4 that the ends (9) and (12) of the spiral spring are bent at substantially right angles to the plane of the spiral and in opposite directions from each other. This construction provides a very simple method of installing the switch lock and one which can very readily be applied to any switch-tongue in use.

When it is desired to apply my improved switch lock, it is only necessary to remove the switch-tongue, mill or chip the recess (6) in the bottom thereof, drill or bore the aperture (8) in the bottom of the recess and the aperture (11) in the top of the base plate, after which the spiral spring and switch-tongue may be placed in position. It will be understood of course that the longitudinal distance between the apertures (8) and (11) should be somewhat less than the distance between the free ends (9) and (12) of the spiral spring in order to provide the necessary tension in the spring. The relation of these apertures in respect to the distance between the ends of the spring can be varied in order to obtain any desired tension.

After my improved switch lock has been installed as described above, and the switch-tongue (3) has been moved to the position shown by full lines in Fig. 1, it will be

readily understood that the tension in the spring (7) acts to hold or lock the switch-tongue in this position. Also when the switch-tongue has been thrown to the position shown dotted in Fig. 1, the spring (7) then acts to hold or lock the tongue in this position. When the switch-tongue is in either of the above positions it is securely locked as described above and thus is prevented from being accidentally moved out of its position by the vibration of the rails caused by a passing train.

It will be understood of course that if the tongue is in the position shown by full lines in Fig. 1 and a train or car is approaching from the side track (2) or in the direction of the arrow, the flange of the wheel will force the tongue laterally toward the dotted position in Fig. 1 and as soon as the tongue 20 has passed the center line "A B" of the switch the spring (7) will force the tongue into the dotted position. In other words the spring (7) permits the tongue to yield sufficiently for the passage of trains in the 25 direction of the arrow in Fig. 1, regardless of which position the tongue may be in at the time.

The spring (7) prevents the tongue from stopping in any intermediate position between the positions shown in Fig. 1, except 30 of course on the dead center line "A B", but when the tongue is thrown to one position or the other by the trainman or switchman, or even when the tongue is forced from the position shown in full lines in Fig. 1 by the flange of a car wheel, it is always 35 thrown past the dead center line "A B" so that there is no liability of its stopping or being stopped in any position except the two 40 positions shown in Fig. 1.

It will therefore be seen that I provide an extremely simple and effective switch lock which absolutely prevents splitting switches.

While I have shown and described my invention as applied to a railway switch-tongue, yet I do not wish to be so limited, as the invention can be very readily applied to many other uses by simply making such slight modifications as are necessary to suit 50 the particular condition.

Having thus fully described my invention, what I claim and desire to secure by Letters Patent is:—

1. A switch lock comprising a switch tongue and a spiral spring secured beneath the said tongue, whereby the tongue is locked in either position from the dead center substantially as described.

2. In a railway switch, the combination 60 with the base plate having the switch tongue pivoted thereto, of a spiral spring, the ends of which operatively engage the top side of

the said plate and the under side of the said tongue respectively, substantially as and for the purpose set forth.

3. In a railway switch, the combination with the base plate, of a tongue pivoted thereto, the said tongue being provided with a recess on the under side thereof, a spiral spring adapted to lie in said recess and having its ends operatively engaging the said plate and tongue respectively, substantially as described.

4. In a railway switch, the combination of a base plate, said plate being provided with an aperture, a tongue pivoted to said plate and provided with a recess, said tongue also being provided with an aperture in the bottom of said recess, and a spiral spring having its respective ends operatively engaging the said apertures, substantially as described.

5. In a railway switch, the combination of a base plate, said plate being provided with an aperture in the top side thereof, a tongue pivoted to said plate, said tongue being provided with an aperture in the bottom side thereof, a spiral spring having its ends bent in opposite directions at right angles to the plane of the spiral, the said 90 ends being adapted to operatively engage the said apertures respectively, substantially as described.

6. In a railway switch, the combination of a base plate, said plate being provided with an aperture in the top side thereof, a tongue pivoted to said plate, said tongue being provided with a recess in the bottom side thereof, said tongue also being provided with an aperture in the bottom of 100 said recess, a spiral spring having its ends bent in opposite directions at right angles to the plane of the spiral, the said apertures being spaced relatively nearer each other than the ends of said spring, said spring 105 being adapted to lie in said recess with the ends thereof operatively engaging the said apertures respectively, substantially as described.

7. In a railway switch, the combination 110 of a base plate, a switch tongue pivoted thereto, the said plate and tongue being provided with apertures, a spiral spring having its ends bent at right angles to the plane of the spiral and adapted to engage the said 115 apertures, the said apertures being spaced relatively nearer each other than the ends of the spring, substantially as described.

In testimony whereof I affix my signature in presence of two witnesses.

SWAN ANDERSON.
